MOUNTING BRACKET

Edward Marshall Shanklin, Charlotte, N.C., assignor to Pneumafil Corporation, Charlotte, N.C., a corporation of Delaware

Application May 8, 1956, Serial No. 583,394

3 Claims. (Cl. 248—289)

This invention relates to a supporting structure, more particularly to a mounting bracket designed to facilitate the mounting of auxiliary equipment in position whereby it may readily be moved to facilitate maintenance of the machinery in conjunction with which said equipment is employed.

Contemporary technological advances are such that a variety of situations arise in which auxiliary equipment is added to existing machine structures, thereby necessitating the provision of supporting members for said auxiliary equipment. Where the auxiliary equipment is merely attached to the machinery in conjunction with which it is employed, difficulties arise when maintenance of the base machinery is required, since access to the base machinery necessitates removal of the auxiliary equipment.

It is thus found that in the textile arts where auxiliary cleaning equipment is provided for cleaning of the textile fabricating machinery, the provision of this auxiliary equipment obviously interferes with ready access to the components of the textile machinery. Suction cleaning equipment of the "Pneumafil" type has been evolved in which the auxiliary cleaning equipment is arranged to offer minimal interference with the operation and maintenance of the machinery. It is found, however, that the control switch boxes ordinarily provided are generally supported in a way interfering with ready access to the auxiliary equipment. "Pneumafil" type suction cleaning equipment generally comprises a system of ductwork arranged adjacent the path of travel of the yarn strands through the textile machinery, be it roving framing, draw frame, spinning frame, or the like. The ductwork leads to a collector unit functioning to separate the collected material from the air stream set up in said ductwork. This collector unit is generally positioned on the end samson of the machinery and arranged to interfere as little as possible with the adjacent floor area, or access to the machinery. Switch boxes are usually supported adjacent the collector unit and in most instances, the positioning of these switch boxes is such that maintenance of the collector unit requires removal of the switch box from the unit, thus creating a fire hazard due to the exposure of electrical connections, and further increases the cost of maintenance due to the increased time required in assembling and disassembling the units.

It is with the above problems in mind that the present construction has been evolved, a construction providing a support bracket for auxiliary equipment which serves to fixedly support such equipment in a desired position, but facilitates the ready movement of such equipment to a position whereby the machinery in conjunction with which said equipment is employed may readily be maintained.

It is accordingly a primary object of this invention to provide a novel supporting structure.

A further object of this invention is to provide a supporting structure for auxiliary equipment whereby said auxiliary equipment may readily be moved to provide

2

access to the machinery in conjunction with which said auxiliary equipment is employed.

Another object of this invention is to provide a supporting structure providing a fixed support in one of two selected positions.

A further object of this invention is to provide a novel supporting means for securely maintaining any auxiliary equipment in position in conjunction with the machinery to which said equipment is applied.

10 It is also an object of this invention to provide a supporting member for auxiliary equipment which serves to facilitate the positioning of such equipment in conjunction with any machinery whereby the positioning of said equipment nowise interferes with the maintenance and repair of said machinery.

An additional object of this invention is to provide a supporting structure for mounting auxiliary equipment of an electrical nature whereby the auxiliary equipment may readily be removed without necessitating disconnection 20 of the electrical components of said equipment.

It is also an object of this invention to provide a supporting structure for the support of auxiliary equipment which serves to secure said equipment against both lateral and axial motion when in operative position.

25 These and other objects of the invention which will become apparent in the following specification and claims are achieved by provision of a vertically extending supporting member, having secured thereto laterally extending attaching portions with appropriate apertures for 30 receipt of securing members from the supported equipment. The vertically extending portion is provided with a coupling portion for attachment to the base machinery.

The coupling portion is provided with an off-set ear having two apertures provided therein. These apertures 35 function, one for permanent securing of the novel supporting member, and the other to facilitate the pivoting of the supporting member and any equipment supported thereby to an inoperative position whereby the machinery to which the auxiliary equipment is attached 40 may readily be maintained.

The specific constructional features of the invention and the mode of operation will be made most manifest and particularly pointed out in conjunction with the accompanying drawings wherein:

45 Figure 1 is a perspective view of the novel supporting bracket; and

Figure 2 is a perspective view of the bracket shown mounted on a collector unit and supporting a switch box in operative position, the unit and box shown in phantom; 50 and

Figure 3 is a perspective view of the arrangement shown in Figure 2 with the bracket supported switch box swung to a position permitting access to the collector unit, the box and unit shown in phantom.

55 Referring now more particularly to the drawings, where like numerals in the various figures will be taken to designate like parts, as best seen in Figure 1, the novel supporting structure 10 here provided comprises an elongate body portion 11 adapted to be secured along the major 60 axis of any equipment to be supported.

Extending transversely of said body portion 11 are two or more laterally extending cross pieces 12 which are designed to be secured to the equipment supported, whereby transverse or axial motion with respect to the body 65 portion 11 will be prevented. These cross pieces are formed with a plurality of apertures designed to facilitate the passage therethrough of screws, bolts, or the like securing members extending into connection with the auxiliary equipment. The cross pieces 12, as is apparent from the drawings, are secured by welding, riveting or the like to the body portion 11.

Extending from each end of the body portion 11 are

coupling portions 14 designed for engaging the machinery. These coupling portions are formed with off-set ears 15 having a bolt hole 16 therethrough, through which a pivoting bolt B may be passed. A locking aperture is formed in this ear in the coupling portion through which a locking pin P may be inserted into connection with the machinery to maintain the mounting bracket in a fixed position, or alternatively, upon removal of said locking pin, to permit switching of the bracket and any auxiliary equipment supported thereon to a position whereby access to the machinery may readily be had. As previously noted, the novel mounting bracket here provided has utility in a variety of situations; by way of illustration, the bracket is here shown as applied to a collector unit C of the "Pneumafil" type to facilitate the mounting of a control switch box S which is ordinarily positioned adjacent the spinning frame to which the "Pneumafil" equipment is attached. By use of the novel mounting bracket here provided, insurance rates can be considerably decreased, since the underwriters are willing to permit a premium discount for those installations which permit removal of the electrical switch box unit without necessitating disconnection of the wires.

Operation

The above disclosed mounting bracket, as illustrated and described, finds particular applicability in textile installations of suction cleaning equipment of the "Pneumafil" type. In a mill installation of Pneumafil suction cleaning equipment, the collector units C are conventionally positioned on the end samsom of the spinning frame. The positioning of the switch box S in conjunction with the collector unit, as previously indicated, engenders a problem in that access to the collector unit for maintenance purposes requires removal of the switch box from the unit, thus necessitating disconnection of the electrical conduits leading to the switch box.

The novel mounting bracket here provided may eliminate the difficulties of switch box removal in a very simple fashion. Thus, the bracket 11 is arranged on collector unit C with bolt B permanently secured in an appropriate tapped aperture of the collector unit. The collector unit is further provided with an aperture for receipt of pin P. Thereafter, switch box S may readily be secured to the cross pieces 12 by means of any conventional fastening elements, such as screws, bolts, rivets, or the like. In use, pin P is inserted in aperture 17 to maintain the switch box S in operative position. When it is desired to obtain access to the front panel of collector unit C, removal of pin P facilitates swinging of switch box S about bolt B to the position illustrated in Figure 3. It will be observed that no disconnection of electrical components is necessitated.

It is thus seen that a simple, inexpensive mounting bracket has been provided, facilitating the positioning of auxiliary equipment in conjunction with machinery,

whereby, though the equipment may be securely maintained in an operative position, it may readily be moved to provide access to the base machinery.

The above disclosure has been given by way of illustration and elucidation, and not by way of limitation, and it is desired to protect all embodiments of the here-indisclosed inventive concept within the scope of the appended claims.

What is claimed is:

1. A mounting bracket for supporting auxiliary equipment on machinery, said bracket comprising an elongate portion adapted to be secured to the equipment; a cross piece on said portion and having means for securement to the equipment; a coupling portion adapted to be secured to the machinery; an off-set ear on said coupling portion and having a hole through which a pivoting bolt is passed; and a removable locking pin inserted through an aperture in said coupling portion for connection with the machinery to secure the bracket thereto.

2. On a suction clearing installation for textile machinery, including a collector unit and a switch box, a mounting bracket supporting the switch box on the collector unit, said bracket comprising: a body portion secured to the switch box; a coupling portion extending from said body portion, straddling the collector unit; an offset ear on said coupling portion having a hole through which a pivoting bolt is passed; a pivoting bolt passed slidably through said hole for connection with the collector unit; and a removable locking pin inserted through an aperture in said coupling portion into the collector unit to secure the bracket thereto, whereby removal of the locking pin permits movement of the switch box to provide access to the collector unit.

3. For use in movably mounting switch box equipment on suction cleaning machinery: mounting means comprising a U-shaped strap member having a body portion and leg portions, said leg portions adapted to straddle the machinery to which the equipment is to be secured; ears on said leg portions, each ear formed with a bolt hole through which a pivot bolt extends, one of said ears having an aperture at a spaced distance from the hole; a locking pin removably inserted in the aperture to prevent pivoting of the member; and cross pieces secured transversely across the body portion to which the equipment is to be secured.
